(57) **CLAIM**

The ornamental design for sound absorbing portions of passenger carrying car, as shown and described.

DESCRIPTION

FIG. 1 is a front view of sound absorbing portions of passenger carrying car;

FIG. 2 is a top view thereof;

FIG. 3 is a right-side view thereof;

FIG. 4 is a left-side view thereof;

FIG. 5 is a bottom view thereof;

FIG. 6 is a partially enlarged view thereof taken from the broken line box 6 in FIG. 3;

FIG. 7 is a front view of a second embodiment of the sound absorbing portions of passenger carrying car shown in FIG. 1, the second embodiment including a surface pattern:

FIG. 8 is a top view thereof;

FIG. 9 is a right-side view thereof;

FIG. 10 is a left-side view thereof;

FIG. 11 is a bottom view thereof; and,

FIG. 12 is a partially enlarged view thereof taken from the broken line box 12 in FIG. 9.

The dot-chain lines depict a boundary between claimed and unclaimed surfaces and form no part of the claimed design. The broken lines depict environmental subject matter only and form no part of the claimed design.
